UNITED STATES PATENT OFFICE.

CLARENCE E. YOUNT, OF HAWARDEN, SASKATCHEWAN, CANADA.

NEEDLE.

1,235,751.

Specification of Letters Patent. Patented Aug. 7, 1917.

Application filed December 29, 1915. Serial No. 69,257.

To all whom it may concern:

Be it known that I, CLARENCE E. YOUNT, a citizen of the United States of America, residing at Hawarden, Province of Saskatchewan, Canada, have invented new and useful Improvements in Needles, of which the following is a specification.

This invention relates to needles, and particularly to sewing machine needles; and it has for its primary object the provision of a needle of this character which will be constructed so as to simplify the operation of threading the same and for eliminating the necessity of having to extend the thread directly into the eye and transversely of the shank of the needle.

Another object of the invention is the provision of a needle of this character which will be constructed so as to positively prevent the accidental disengagement of the thread from the eye or any working of the eye into the guideway formed in the shank of the needle.

Another object of the invention is the provision of a needle of this character wherein the entrance guide for the thread will be positioned at such point on the shank so that when the needle is used upon relatively heavy work the guide will serve as a brace to strengthen the needle and prevent the shank from being accidentally separated from the stock.

With these and other objects in view, the invention consists of certain novel features of construction, combination and arrangement of parts, as will be hereinafter described and claimed.

In the accompanying drawings:—

Figure 1 is a perspective view of the needle, showing the application of the needle in the ordinary foot; and

Fig. 2 is a longitudinal section through the needle.

The needle as herein designed is provided with any suitable well known form of stock or attaching portion 1 which is adapted to be connected in the customary manner with the foot 2 and to be secured in place thereto by means of a fastening screw 3. From the stock 1 extends a shank 4 pointed at its lower end, as at 5, and provided with an eye 6 of substantially elliptical form.

The said shank 4 is split longitudinally to form a thread guide 7 having a lower curved branch 8 provided with a lateral portion 9 which opens directly into the eye

6 at one side thereof and in such manner that the portion 10 of the eye forms a guard to prevent the thread after it is extended through the eye from being accidentally drawn into the portion 9 and into the guide 7. The needle as thus designed will be found extremely desirable for use by persons having poor eye sight and under ordinary conditions its use will result in a material saving of labor, particularly when such materials as silk or the like are to be used by the needle. The shank at its point of juncture with the stock 1 is provided with a pair of lugs 11, 11 which extends approximately at an angle of 90° to the axis of the shank and which are arranged relatively so as to form an initial guideway 12 which opens at 13 into the main longitudinal guide 7. The inner surfaces of the lugs 11, 11 are slightly curved longitudinally along their inner surfaces so that at their outer ends the surfaces collectively present a relatively large flared mouth by means of which the thread may be readily extended into the main guide 7. At 14, the inner surfaces of the lugs 11, 11 approximately come together so that the upper lug forms a brace for the lower lug and both lugs form a brace for the shank of the needle when the needle is used upon heavy fabric and the needle penetrates the fabric to a point where it is brought to bear against the under lug 11.

When threading the needle the terminal 90 of the thread is placed in a horizontal position and held between the fingers of the hand of the operator and pressure in a horizontal direction is brought against the thread to cause the same to enter between 95 the lugs 11, 11 and finally become positioned at the axial center of the shank 4. Pressure in a downward direction is then applied against the thread and finally the thread is brought to a position where it will enter the 100 lateral branch 9 of the portion 8 and it may be then made to freely enter the eye 6.

I claim:—

A sewing machine needle provided with an eye and also provided with a longitudinal 105 guide way forming a split in the needle and extending from the eye to a point spaced from the eye and at one side of the needle, so that a spring portion is formed between the split, eye, and the upper end of the split, 110 the needle being provided with a laterally extending lug at a point coincident with the

upper end of the split and the spring portion of the needle being also provided at its upper end with an outwardly extending lug normally bearing directly under and against the first named lug and coacting therewith to normally close the upper end of the split and to strengthen and brace the needle.

In testimony whereof I affix my signature in presence of two witnesses.

CLARENCE E. YOUNT.
